ALBERT BOOTHE, OF COLFAX, IOWA.

STRINGED MUSICAL INSTRUMENT.

Application filed April 30, 1923. Serial No. 635,697.

This invention relates to musical instruments, and has special reference to a stringed instrument of the guitar and zither type, which I preferably term a "sirelin."

5 One important object of the invention is to provide an instrument of the guitar or zither character with novel arrangement of strings, bridges and frets whereby a tone may be created which somewhat resembles that of a

10 Hawaiian guitar.

A second important object of the invention is the production of a novel form of musical instrument in which there is an improved arrangement of strings which are 15 sounded by plucking and fretting, being employed for each set of strings.

The invention consists in general of certain novel details of construction and combinations of parts hereinafter fully described, 20 illustrated in the accompanying drawings and specifically claimed.

In the accompanying drawings like characters of reference indicate like parts in the several views, and:

25 Fig. 1 is a front view of an instrument constructed in accordance with this invention.

Fig. 2 is a side view thereof.

Fig. 3 is a detail view of a combined nut 30 and fret for the long and short strings.

In the embodiment of the instrument herein disclosed, it will be seen that there is provided a hollow body 10, the general shape of the body beyond the sound hole being that 35 of the ordinary guitar, but slightly wider in the proportion of its length. This body has a sound hole 11, and from the upper end of the body to one side of its longitudinal center projects the neck 12 whereon is the head 40 13 carrying the tuning pegs 14. The neck and head may be of the usual guitar type the neck 12 being provided with the usual frets 15, and extending along this neck and over the body 10 are the strings 16. These strings 45 pass over and bear upon a bridge 17 adjacent the rounded end of the instrument, and are connected to the usual pegs 18 on the end of the body.

It will be noted that the strings 16 extend 50 from pegs 14 over the frets 15 and the combined bridge and fret 24, and between the sound opening 11 and the bridge 17 there is a fret 22, the same constituting one of the series of frets for the strings 21. The frets 55 15 are spaced so that the distance will diminish from the head 13 toward the body, and in

use these strings are tuned in fifths, the notation of these strings from the bass to the treble side being E, B, F $\sharp$ and C $\sharp$. At one side of the neck there is provided an auxiliary 60 head 19 carrying the tuning pegs 20, and connected to these pegs are the three bass or 65 accompaniment strings 21. These strings from left to right are tuned as follows: E, G $\sharp$, B.

It is to be noted that the tuning of strings E, G $\sharp$ and B is in thirds. The combined nut and fret 24 has a portion over which strings 21 pass, the portion with which the strings 21 engage being of the same height as the 70 height of the bridge 17 which extends entirely across the two sets of strings and constitutes a tail bridge. The accompaniment strings may be played open and the treble or air strings played either open or by aid 75 of the frets 15 in the usual manner. While the instrument may be used in this way, special provision is made for utilizing the instrument in an entirely different manner. To this end across the body 10 beneath the 80 two sets of strings, and in spaced relation to the tail bridge 17, there is provided a long fret 22. Beneath the strings 21 between the long fret 22 and the tail bridge 17 is arranged 85 a series of auxiliary frets 23, and this series is also carried up the body a short distance above the long fret 22, as can be clearly seen in Fig. 1. The frets 23 are so placed that when a string is moved against one of these frets by pressing the string downward with 90 the fingers between the particular fret in question and the next fret toward the tail bridge 17, the string between the selected fret and the combined nut and fret 24 just below the pegs 20 is fretted and plucked to produce 95 a note that accords with the part of the string that is free to vibrate. In like manner, owing to the position of the long fret 22, the pressing downward on one of the strings 16 between the long fret 22 and the tail bridge 17 100 simultaneously produces a note, the tone of which is regulated by proper fretting on the neck 12.

It is to be understood that tones on this instrument are preferably produced by fretting 105 and plucking of the strings and that, while the effect may be varied at times by plucking the strings with picks, the principal purpose of the arrangement is to enable selected tones to be produced by fretting and plucking in the usual manner. Under these circumstances, it will be noted that one of the strings

16 may be moved downward and held, and so long as it is thus held the portion of such string between the long fret 22 and the point at which it is fretted on the neck will vibrate, 5 and will continue to vibrate until it slowly comes to rest. Meanwhile, one or more of the strings 21 may be fretted at different positions since the finger may be slid along the string 16 during the plucking of the strings 10 21 without changing the tone.

It will also be noted that by holding the strings downward at the nodal points, clear harmonics are produced, and that impressions may be given to the music played on this instrument by the varying degrees of force with 15 which the strings are plucked, and by varying the pressure of the strings with the frets.

There has thus been provided a simple and 20 efficient device of the kind described and for the purpose specified.

It is obvious that minor changes may be made in the form and construction of the invention without departing from the material spirit thereof. It is not, therefore, desired to confine the invention to the exact 25 form herein shown and described, but it is desired to include all such as properly come within the scope claimed.

The construction of the instrument provides an end bridge 17 for all the strings and 30 the strings 16 overlie the long fret 22, which is an extension of one of the frets for the strings 21. The bridge 24 for the strings 21 being reduced in height serves as one of the 35 series of frets 15 for the strings 16.

The instrument hereinbefore described can be played after the manner of a Hawaiian guitar or banjo ukulele. In playing, both hands are used, the instrument being held in 40 the lap, or, if desirable, it may be placed upon a stand or table.

Having thus described the invention, what is claimed as new, is:

1. A stringed musical instrument of the 45 guitar type comprising a body, a neck having a head, the neck being attached to and extending from the end of the body and to one side of the longitudinal center thereof, an auxiliary head which extends laterally from the 50 neck to a point beyond the longitudinal center of the body, pegs for connecting strings to the heads and to the body of the instrument, a series of frets carried by the neck and body over which strings attached to the head on 55 the neck pass, a series of frets attached to the body over which strings attached to the

auxiliary head pass, a tail bridge common to both sets of frets, a fret constituting one of the series for the strings which extend from the auxiliary head, said fret underlying the 60 strings which overlie the neck, and a combined bridge and fret located adjacent to the auxiliary head and extending to constitute one of the series of the frets for the strings which engage the head on the neck. 65

2. A stringed musical instrument comprising a body of the guitar type, the belly having therethrough a transversely elongated sound opening which is located centrally and to one side of the transverse center of the 70 belly, a fretted neck located to one side of the longitudinal center of the body, an auxiliary head attached to the body and extending laterally from the neck, a series of frets attached to the belly between the sound opening and the tail portion of the body, a set of strings which overlie the frets between the sound opening and the tail portion of the body, a set of strings which overlie the body and the fret of the 75 neck, and a tail bridge common to both sets of strings.

3. A stringed musical instrument comprising a resonant body having to one side of its longitudinal center a neck and head and on 80 the opposite side of its longitudinal center a head which is attached to the neck and body, pegs carried by the respective heads, a sound opening through the belly of the body of such area as to extend beyond parallel sets of 85 strings carried by the pegs which engage the heads and the tail end of the body, frets carried by the neck, a series of frets attached to the belly of the body between the tail end of the body and the sound opening, and a tail bridge which is common to the parallel sets of 90 strings. 95

4. A stringed musical instrument of the character shown comprising a resonant body provided with a fretted neck and a head, a laterally extending head attached to the body, the belly of the body having a sound opening therethrough of such area as to be overlain by strings attached to the respective heads and the end of the body, a series of frets attached to the body between the sound opening and the tail end of the body, a bridge for all of the strings attached to the body adjacent to the tail end thereof, and a single fret which underlies both sets of strings. 100 105
